UNITED STATES PATENT OFFICE.

ISAAC SNOW, OF LAWRENCE, MASSACHUSETTS, ASSIGNEE TO DRAPER CORPORATION,
OF HOPEDALE, MASSACHUSETTS, A CORPORATION OF MAINE.

FEELER MECHANISM FOR LOOMS.

Application filed August 6, 1923. Serial No. 655,815.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms whereby the filling may be replenished from time to time. In that type of feeler mechanisms wherein the feeler is given a movement in a direction longitudinally of the shuttle to effect replenishment, it is the usual practice to adjust the feeler a predetermined distance from the rear or head end of the bobbin to properly cooperate with the filling and to call the change when the filling is substantially exhausted. In view of the diversity of kinds of filling wound bobbins or carriers used in some looms, it consequently becomes necessary to adjust the feeler each time the character of the filling wound bobbins or carriers is changed, and especially is this the case where the same loom employs at one time filling wound bobbins or carriers wherein the windings at the initial stage are more flat or cylindrical than the filling wound bobbins or carriers used at other times in the loom, wherein the windings are more abrupt or are of the "short conical wind." For instance, if the feeler is adjusted to suit the long flat wound filling carriers or bobbins, and then the same loom employs the short conical wound filling carriers or bobbins, the feeler is liable to call the change when a working supply of filling is still present in the short conical winds and consequently produce much waste.

One of the objects of the present invention is to provide a feeler mechanism in which the feeler shall be so constructed that without adjustment it may be used with either character of filling wound bobbins or carriers, and in accordance with the present

invention the feeler has pivotally mounted thereon a preventer tip which, when the filling on the bobbin presented to the feeler is substantially exhausted but there still remains a working supply in the short conical wind, the preventer tip is caused to engage the short conical winds and prevent premature side swipe movement of the feeler.

The various features and new combination of parts pertaining to the present invention will best be understood from the following description and the accompanying drawings of one good, practical form thereof.

In the drawings:

Fig. 1 is a perspective view of a feeler mechanism containing the present invention, some of the parts being broken away;

Fig. 2 is a rear end perspective view of the filling engaging end of the feeler;

Fig. 3 is a plan view showing the action of the feeler when a working supply of filling is present in the shuttle on a detecting beat;

Fig. 4 is a similar view showing the action of the feeler mechanism when the filling portion of the filling carrier or bobbin presented to the feeler is substantially exhausted of filling but there yet remains a working supply of the short conical wind;

Fig. 5 is a plan view of the feeler and the relative position of parts when the filling of the short conical wind has reached or nearly reached a degree of substantial exhaustion; and

Fig. 6 is a view similar to that of Fig. 5 showing the filling of the short conical wind substantially exhausted and the feeler partaking of its sideswipe movement.

Since the present invention is more directly concerned with the feeler itself rather than with the replenishing mechanism or the means between the feeler and the replenishing mechanism for effecting replenishment of filling, it has not been deemed necessary to show herein the filling replenishing mechanism or details of the

means for setting it in operation when the feeler is moved longitudinally of the shuttle on a detecting beat. The details of these parts may be similar to those already well-known.

In the present illustration of the invention the feeler is shown as of the inclined type which is mounted to enter the shuttle on a detecting beat in a direction inclined 10 to the longitudinal axis of the shuttle, but the invention itself and its advantages may be utilized in other types of feeler mechanisms wherein the feeler is moved longitudinally of the shuttle to call for a change of 15 filling.

Extending from the front of the loom frame is the shipper stand 1 to which the feeler mechanism may be connected in usual manner. In the present instance the feeler 20 stand 2 is provided with a slot 3 through which passes the bolt 4 for securing the feeler stand in the desired adjusted position.

Mounted at the front of the feeler stand is the rocking bearing 5 supported for rocking movement by a bracket 6 secured to the feeler stand by a bolt 7. At the rear portion of the feeler stand is a guideway 8 which forms a support for a slide 9 to which is connected a transmitter 10 associated with the means for initiating replenishment of filling when the feeler partakes of its sideswipe movement. The slide 9 has the opening 11 through which the feeler 12 extends, the front end portion of 35 the feeler being passed through an opening in the rocking bearing 5. Secured to the feeler 12 is the bridge 13 between which and the rocking bearing 5 is interposed a spring 14 normally tending to hold the 40 feeler in its rearward feeling position, and the rear portion of the feeler is provided with a filling engaging end 15 preferably provided with a roughened surface or tooth 16, the construction being such that should 45 a working supply of filling be present in the shuttle on a detecting beat, the roughened or toothed end of the filling engaging portion 16 will sink into the filling and prevent movement thereof in a direction longitudinally of the shuttle. Should, however, the portion of the filling carrier or bobbin which is presented to the filling engaging end of the feeler be substantially exhausted of filling, the feeler will be 50 moved longitudinally along the filling carrier and call the change. The parts and constructions so far described and as shown are and may be substantially the same as shown and described in the patent to Edward S. Stimpson, No. 1,309,226, dated July 8, 1919.

The shuttle box 17 may be of usual construction and provided with an opening in its front wall for the entrance of the feeler,

as usual, and similarly the shuttle 18 may 65 be provided with an opening 19 which registers with the opening in the front wall of the shuttle box on a detecting beat to permit the feeler to enter the shuttle and feel for the filling. The shuttle 18 is provided with the usual bobbin holding jaws 20 which engage the usual rings 21 on the filling carrier or bobbin 22.

Pivottally mounted on the feeler at 23 is the preventer tip 24 which extends laterally to each side of the feeler and, as shown in the present instance, the feeler preventer 24 is provided with a filling engaging tooth 25 at one side of the feeler and a bobbin or filling engaging portion 26 at the opposite side of the filling engaging end of the feeler.

The preventer tip 24 may be variously contrived and connected to the feeler but in the present instance it is formed of sheet metal and bent upon itself as at 27 to provide the upper and lower embracing leg portions between which the filling engaging end 15 of the feeler extends. The preventer tip may be stamped out of sheet metal conveniently and bent as described to provide the filling engaging tooth 25 and the bobbin or filling engaging portion 26. The edge portions of the connecting wall 27, as at 28 and 29, form a stop for limiting the free swinging movement of the preventer tip.

Should a filling carrier or bobbin of the long or flat filling wind be employed in the shuttle, the feeler stand is adjusted to position the feeler for engagement with the filling carrier or bobbin or the filling thereon at a point some distance from the head of the bobbin, and when the filling is substantially exhausted on a detecting beat the toothed end portion 16 of the filling engaging end of the feeler will not be held from its sideswipe movement, and the feeler will call for a change of filling as usual. Should a filling carrier having short conical winds be employed in the shuttle, as indicated in Fig. 4, and the portion of the filling carrier or bobbin be presented to the filling engaging end of the feeler with the filling thereon substantially exhausted, as indicated in Fig. 4, the toothed end portion 16 of the feeler will tend to slip longitudinally along the filling carrier or bobbin, but should a working supply of filling be present in the short conical wind adjacent the bobbin head, as indicated in Fig. 2, the toothed end portion 25 of the preventer tip will engage the conical wind and prevent premature movement of the feeler longitudinally along the filling carrier or bobbin, until, when the filling is substantially exhausted in short conical winds, as indicated in Fig. 6, the tooth 25 will no

longer hold the feeler from its sideswipe movement and a change of filling will be called.

The engaging end portion 26 of the preventer tip insures a holding engagement of the tooth 25 of the preventer tip with the short conical winds by coming in contact with the denuded or substantially denuded portion of the filling carrier or bobbin at 10 the opposite side of the filling engaging end of the feeler and causes the tooth 25 to sink into the short conical winds, as indicated in Figs. 4 and 5, until when the reserve supply of filling in the short conical 15 winds has itself become substantially exhausted, as indicated in Fig. 6, the tooth 25 will no longer be held by the now substantially exhausted windings of the short conical winds and the feeler will then be free to 20 partake of its sideswipe movement to call for a change of filling.

Thus, without any change in the adjustment of the feeler, the feeler mechanism of the present invention may be employed 25 in connection with either long flat conical winds of filling on the filling carriers or bobbins or with the short conical winds, without the production of undue waste and without readjustment of the feeler.

30 What is claimed is:

1. In a feeler mechanism for looms, the combination of a feeler having an end to enter the shuttle on a detecting beat and by engagement with the filling prevent replenishment until the filling is substantially exhausted, and a preventer tip pivotally connected to the feeler for bodily movement therewith along the filling carrier and having a holding tooth to prevent the feeler calling 40 for a change of filling when the filling opposite the feeler is substantially exhausted but a working supply of filling is engaged by the holding tooth of preventer tip.

2. In a feeler mechanism for looms, the combination of a feeler mounted to enter the shuttle in a direction inclined to the longitudinal axis thereof and having an end which by engagement with the filling prevents the feeler from calling for a change 50 of filling until substantial exhaustion of the filling engaged by it, and a preventer tip pivotally mounted on the feeler for bodily movement therewith along the filling carrier and extending to one side of the feeler to 55 prevent the feeler from calling for a change of filling when that engaged by the feeler end is substantially exhausted but a working supply at one side of the feeler end is engaged by the pivoted preventer tip.

60 3. In a feeler mechanism for looms, the combination of a feeler mounted for movement in a direction longitudinally of the shuttle to initiate filling replenishment and held from such movement by engagement

with the filling until substantial exhaustion 65 of the filling engaged by it, and a preventer tip pivotally mounted upon the feeler for bodily movement therewith as the feeler moves along the filling carrier to call for a change of filling and having a tooth at one 70 side of the filling engaging end of the feeler to prevent the feeler calling for a change of filling when that opposite the feeler end is substantially exhausted but a working supply of filling is engaged by the tooth of the pivoted preventer tip. 75

4. In a feeler mechanism for looms, the combination of a feeler mounted for movement in a direction longitudinally of the shuttle to initiate replenishment of filling and held from such movement by engagement with the filling until substantial exhaustion of the filling presented to the feeler, and a preventer tip pivotally mounted on the feeler and having filling engaging portions 80 at each side of the feeler end, one of which is constituted as a tooth to engage a working supply of filling at one side of the feeler and prevent movement of the feeler to call the change when the filling on the filling carrier presented to the feeler is substantially exhausted but a working supply at one side of the feeler end is engaged by the tooth of the pivoted preventer tip. 85

5. A feeler having a toothed filling engaging end and mounted for movement longitudinally of the shuttle, and a preventer tip pivotally mounted on the feeler and having a filling engaging portion at each side of the toothed filling engaging end of the feeler. 90

6. A feeler having a toothed filling engaging end and mounted for movement longitudinally of the shuttle, a preventer tip pivotally mounted on the feeler and having a filling engaging portion at each side of the toothed filling engaging end of the feeler and a stop for limiting the swinging movement of the pivoted preventer tip. 100 105

7. A feeler having a toothed filling engaging end and mounted for movement longitudinally of the shuttle, and a preventer tip pivotally mounted on the feeler and having a filling engaging portion at each side of the toothed filling engaging end of the feeler one of which is constituted as a filling engaging tooth. 110 115

8. In a feeler mechanism for looms, the combination of a feeler having a filling engaging end and mounted for movement in a direction longitudinally of the shuttle, and a preventer tip pivotally mounted on the feeler and extending to each side of the filling engaging end of the feeler, one of the extensions having a tooth and the other a portion to engage the filling or filling carrier to set the toothed portion into the filling when a working supply is presented to 120 125

the toothed portion and the filling is substantially exhausted opposite the engaging end of the feeler.

9. In a feeler mechanism for looms, the combination of a feeler mounted for movement longitudinally of the shuttle and adapted for use in connection with long flat wound filling carriers and short conical filling wound carriers, comprising a filling

engaging end, and a preventer feeler tip 10 pivotally mounted on the feeler and extending to opposite sides of the filling engaging end of the feeler, one of said extensions being provided with a tooth.

In testimony whereof, I have signed my 15 name to this specification.

ISAAC SNOW.
